UNITED STATES PATENT OFFICE

154,370

DESIGN FOR A UNIVERSAL TOOL FOR
WATCHMAKERS

Charles Croutch, Los Angeles, Calif.

Application September 23, 1946, Serial No. 133,514

Term of patent 14 years

(Cl. D54—13)

To all whom it may concern:

Be it known that I, Charles Croutch, a citizen of the United States of America, residing in the city of Los Angeles, in the county of Los Angeles, State of California, have invented a new, original, and ornamental Design for a Universal Tool for Watchmakers, of which the following is a specification, reference being had to the accompanying drawing, forming a part thereof.

Fig. 1 is a perspective view of a tool showing my new design with jaw portions shown separated therefrom;

Fig. 2 is a top plan view of the tool shown in Fig. 1;

Fig. 3 is an elevational view of the tool with the jaw portions in place; and

Fig. 4 is a bottom plan view of the tool.

I claim:

The ornamental design for a universal tool for

watchmakers, substantially as shown and described.

CHARLES CROUTCH.
